UNITED STATES PATENT OFFICE.

ROBERT BROWN, OF DONAGHMORE, IRELAND.

SHAVING-STICK.

1,357,026.

Specification of Letters Patent. Patented Oct. 26, 1920.

Application filed January 22, 1919. Serial No. 272,574.

To all whom it may concern:

Be it known that I, ROBERT BROWN, a subject of the King of Great Britain, residing at Donaghmore, county Tyrone, Ireland, have invented certain new and useful Improvements in Shaving-Sticks, of which the following is a specification.

The object of this invention is an improved arrangement of shaving stick in which the soap portion of the stick is held within a head or holder in such manner as to waste a minimum amount of soap and to insure that no rough or sharp surface can rub against the face of the user.

15 The invention is best described by reference to the accompanying drawings in which Figure 1 is a perspective view of the head while Fig. 2 is a sectional elevation of the head showing the stick of soap and arranged 20 in a cardboard or metal case. Fig. 3 is a cross section showing a modified form of head.

In Figs. 1 and 2, the head, is provided with an internal flange 2, which has a convex curvature with respect to the end of the stick which has to be applied to the face. 25 3 is a convex boss, while 4 is an external flange.

The soap is filled into the head by placing 30 a cylinder (not shown) over the internal flange of the head, and forcing in the soap by means of a plunger.

The head is arranged to fit inside a container 6, which may be made of metal or 35 cardboard, and it will be seen that by the method of filling described above, the soap 5 is out of contact with the container 6.

When the stick is used, it will be seen that it is firmly held by the head 1, although only 40 a minimum quantity of soap is inclosed between the flange 2 and the boss 3. When the soap has all been used, the face comes into contact either with the curved surface of the internal flange 2 or with the smooth surface 45 of the boss 3.

Fig. 3 shows a modification in which the convex boss 7 of somewhat different form, is employed. In this case the curved internal flange may be replaced by a bead 8. Otherwise the arrangement is the same as in 50 Fig. 2.

If desired, the head shown in Fig. 1 may be made of metal all in one piece.

I declare that what I claim is:—

1. A shaving stick and holder formed of a 55 stick of soap held within a shallow cylindrical metallic cap having an internal projection and an internal boss whereby an annular space is left between the boss and the interior of the cylinder and its projection 60 which space is filled with soap and a naked projecting stick of soap of the required length projecting from the cylinder head.

2. A shaving stick holder formed of a shallow cylindrical cap having an internal convex boss and an internally smooth edge annular projection whereby an annular space is left between the boss and the interior of the cylinder, a stick of soap made to fill the interior of the cap and projecting therefrom, and a box fitting the outside of the cap, and standing clear of the soap or any wrapper around it.

3. A shaving stick formed of a shallow cylindrical metal cap having an internal convex boss gradually curving from the cylinder walls inward and an internal annular projection with the said head and a stick of soap filling the head and projecting therefrom.

In witness whereof, I have hereunto signed my name this 30th day of December, 1918, in the presence of two subscribing witnesses.

ROBERT BROWN.
